TUBING ANCHOR

John S. Page, Long Beach, Calif., assignor of one-tenth to Betty Lee McLaughlin, Los Angeles, Calif.

Application July 11, 1942, Serial No. 450,516

14 Claims. (Cl. 103—219)

This invention has to do with well equipment and has more particular reference to tubing anchors. A general object of this invention is to provide a simple, practical and very effective tubing anchor.

When an oil well or the like is equipped with a pump it is customary to install a string of tubing in the well to carry the pumped fluid to the ground surface and to arrange the pump at the lower end of this tubing. The long string of tubing has substantial flexibility and elasticity and during operation of the pump the tubing "works" up and down. This working of the tubing is caused by movement of the fluid column within the tubing, by the friction between the relatively reciprocable pump plunger and pump barrel and by the alternate imposition and relieving of the weight of the fluid column on the pump, which accompanies the pump-operating movements of the pump rod. The movement or "working" of the tubing produces wear between the tubing and the well casing and often causes holes to be worn in the casing and also wears the couplings of the tubing string so that they leak and sometimes fail.

Another object of this invention is to provide a tubing anchor that effectively prevents working of the tubing.

Another object of this invention is to provide a tubing anchor that serves to maintain the tubing under tension or in a "stretched" condition so that it cannot stretch further and cannot contract during the pumping operations. When a conventional tubing anchor is used the tubing is relieved of a portion of its weight thereby causing slack in the tubing and allowing the above described "working" of the tubing. Where the tubing anchor of the present invention is employed the tubing is held under tension so that there is no slack and no possibility for the tubing to work.

Another object of this invention is to provide a tubing anchor that is actuated and held actuated by the head or hydrostatic pressure of the column of fluid in the tubing and that is released or conditioned for ready release when the fluid column is drained from the tubing. No manipulation of the tubing string is required for either the operation or the release of the anchor of this invention. The operation of the anchor is entirely automatic and the tubing need not be disturbed to control or operate the anchor.

Another object of this invention is to provide a tubing anchor that is positive in operation and

that remains positive and effective so long as the fluid column occupies the tubing string.

Another object of this invention is to provide a tubing anchor of the character referred to that is extremely simple in construction and that is not subject to becoming "sanded up" or made inoperative by accumulations of sand.

A further object of this invention is to provide a tubing anchor of the character mentioned that does not restrict or in any way interfere with the movement of fluid through the tubing and that may be interposed in the tubing string at any selected point or points without necessitating alteration of the tubing string assembly.

The various objects and features of my invention will be fully understood from the following detailed description of a typical preferred form and application of my invention, throughout which description reference is made to the accompanying drawing, in which:

Fig. 1 is a side elevation of the improved anchor of this invention in position in the well tubing prior to actuation. Fig. 2 is an enlarged longitudinal detailed sectional view taken substantially as indicated by line 2—2 on Fig. 1, showing the anchor in the actuated condition and Figs. 3, 4 and 5 are transverse detailed sectional views taken as indicated by the line 3—3, 4—4 and 5—5, respectively, on Fig. 2.

In the drawing, C designates the well casing and T designates a portion of the well tubing extending through the casing. It will be assumed that the tubing T extends from the well pump, not shown, to the top of the well where it may be secured to the usual tubing head. The anchor of the invention may be connected in the string of well tubing T at any selected or desired point and, if desired, two or more of the anchors may be incorporated in the tubing string at vertically spaced points.

The tubing anchor of this invention may be said to comprise, generally, a tubular body 10 to be connected in the tubing string T, means 11 on the body for gripping the casing C and means 12 for operating the gripping means 11.

The body 10 serves to carry or mount the various other parts of the tool and, in accordance with the invention, is a simple unit that may be readily interposed in the string of tubing T.

The body 10 is an elongate tubular structure or member. In the particular case illustrated the body 10 comprises two sections 13 and 14, it being understood that the body 10 may be an integral element if desired or found practical. The upper and lower sections 13 and 14 are connected by a

suitable threaded collar or coupling 15. The longitudinal opening 16, extending through the tubular body sections 13 and 14, is preferably of the same diameter or fluid capacity as the opening in the tubing string T so that the body offers no resistance or obstruction to the fluid flow and does not interfere with pump rod movement. In the case illustrated the opening 16 in the upper body section 13 is enlarged at its upper end and is screw-threaded so that the body section 13 may be directly screwed onto the tubing T. The lower portion of the lower body section 14 is enlarged to have, what I will term, a chamber 17. An adaptor or sub 18 may be screw-threaded into the lower end of this chamber 17 and may be screwed into a coupling 19 of the tubing T to secure the lower end of the body 10 in the tubing string. The enlarged lower portion of the body section 14 just referred to has a flange or wall 20 of substantial vertical extent or thickness. This wall 20 occurs at the upper end of the chamber 17 and its function will be later described. The exterior of the enlarged lower portion of the body 10 may be provided with circumferentially spaced grooves or channels 9 to provide for the free passage of fluid. It will be observed that the body 10 just described is a simple inexpensive structure.

The means 11 is provided to grip the casing C to hold the tubing T against movement and more particularly is operable to maintain the tubing T under tension so that it cannot work up and down during operation of the well pump. The means 11 is in the nature of a wedge means or slip means and comprises two or more spaced wedge abutments or wedge faces 21 on the body 10. In the preferred arrangement the means 11 is carried on the upper body section 13 and there is a plurality of spaced wedge faces 21. The body section 13 is provided with circumferentially spaced vertical or longitudinally extending ribs 22 whose outer surfaces are pitched or sloped to constitute the slip actuating faces 21. As best illustrated in Fig. 3 of the drawing, the ribs 22 are spaced apart to leave ample fluid passages between them. It is preferred to provide the slip faces 21 with dove-tailed splines or ribs 23.

The casing gripping means 11 further includes slips 24 which cooperate with the inclined faces 21. The slips 24 are wedge parts having sloping inner surfaces which cooperate with the inclined faces 21 and having roughened or toothed outer sides curved to conform to the internal surface of the casing C. The pitched or inclined inner sides of the slips 24 are provided with dove-tailed or undercut grooves 25 which slidably receive the tongues 23 to retain the slips in sliding cooperation with the faces 21. The outer or active faces of the slips 24 preferably have teeth 26 for gripping with the internal surface of the casing C. In accordance with the invention the teeth 26 face upwardly and outwardly so that they are particularly effective in gripping the casing C to prevent upward movement of the tubing T. In this connection it is to be observed that the slips 24 have teeth of a different pattern or disposition than conventional slips. Conventional slips have teeth which are pitched in the opposite direction to their sloping inner sides. In the present invention the teeth 26 are pitched in the same general direction as the inclined inner sides of the slips 24 to hold the tubing T against upward movement.

The gripping means 11 preferably includes

means for operatively connecting the several slips 24 for simultaneous operation. This means may include a tube or sleeve 27 shiftably or slidably engaged around the body 10 to move vertically thereon. In practice the sleeve may surround the upper portion of the body section 14 and engage around the collar 15. Thus, the sleeve 27 is spaced between the slips 24 and the wall 20. The several slips 24 are linked or connected with the shiftable sleeve 27. In the construction illustrated the lower ends of the slips 24 have spaced lugs 28 and the upper end of the sleeve 27 has similar aligned pairs of lugs 29. Links 30 have their opposite end portions received by the pairs of spaced lugs 28 and 29 and pivot pins 31 and 32 carried by the lugs pass through openings in the links to pivotally connect the links with the slips and sleeve. It will be seen how the links 30 connect the several slips 24 with the sleeve 27 for simultaneous vertical movement therewith, while allowing free radial projection and retraction of the slips.

It is preferred to provide the tool with means for yieldingly holding the slips 24 in the retracted positions so that the anchor may be run down through the casing on the tubing T without interfering with the casing, which means also aids in retracting the slips when the tubing T is to be withdrawn from the well. This means is preferably associated with the sleeve 27 to hold the sleeve in a position where the plurality of slips is retracted. The means for yieldingly holding the slips 24 retracted includes a spring 33 surrounding the body section 14 and housed within the sleeve 27. The internal diameter of the sleeve 27 is reduced adjacent the lower end of the sleeve providing an upwardly facing internal shoulder 34. The major portion of the sleeve 27 surrounds the body section 14 with considerable clearance and engages over the collar 15 with suitable working clearance. The spring 33 is housed or received within the sleeve 27 and is arranged under compression between the shoulder 34 and the lower end of the coupling or collar 15. The spring 33 acting downwardly against the shoulder 34 yieldingly urges the sleeve 27 to the position where the slips 24 are retracted as shown in Fig. 1 of the drawing. It will be observed that the spring 33 is effectively housed and protected in the sleeve 27. The sleeve 27 engages about the body section 14 and collar 15 with sufficient clearance so that there is no dashpot action accompanying movement of the sleeve which might retard retraction or expansion of the slips 27, as the case may be.

The means 12 is a fluid pressure actuated means being operable by the hydrostatic pressure of the column of fluid within the tubing string T. The means 12, when actuated, is operable to hold the tubing T against movement and, as will be later described, serves to hold the tubing string under tension, that is, it operates to prevent upward movement of the tensioned tubing. In accordance with the invention the means 12 includes one or more cylinders 35 and pistons 36 operable therein. In the construction illustrated one or more cylinder openings 35 are formed in the wall 20. With the particular construction disclosed there are three circumferentially spaced vertical cylinder openings 35 axially aligned with the ribs 22 and slips 24, it being understood that there may be any selected or required number of cylinder openings spaced and arranged as found most desirable. The cylinder openings 35 may be plain cylindrical openings

of uniform diameter extending upwardly from the chamber 17 to the upper end of the wall 20. A piston 36 operates in each cylinder opening 35. The pistons 36 may be solid cylindrical members of sufficient length to extend completely through the cylinder openings 35 and project from the end of the openings when in the unactuated positions. It is preferred to provide the pistons 36 with sealing rings 37 formed to effectively seal with the walls of the cylinder openings 35.

The upper ends of the pistons 36 are operatively associated or engaged with the sleeve 27. In the simple construction illustrated the upper ends of the pistons 36 have heads 38 presenting flat faces which engage upwardly against the lower end of the sleeve 27. The sleeve 27 may have bosses or enlargements 39 adjacent its lower end to have complete engagement with the piston heads 38. The pistons 36 are formed and proportioned so that the sealing rings 37 never leave the cylinder openings 35 and the heads 38 are engageable with the wall 20 to limit downward movement of the pistons. In accordance with the invention the pistons 36 are of sufficient length to either project into the chamber 17 or to have their lower ends flush with the upper wall of the chamber 17 when the pistons and slips 24 are in the fully actuated positions. With the pistons 36 engaged in the cylinder openings 35, as just described, the lower ends of the pistons are exposed to the hydrostatic pressure existing in the tubing T under normal pumping conditions and this pressure acts upwardly on the pistons to maintain them in the positions illustrated in Fig. 2 of the drawing where the slips 24 are fully actuated.

In the use or operation of the tubing anchor provided by this invention the anchor is interposed in the string of tubing T at the selected point when the tubing is assembled and run into the well. The tubing T may be completely assembled and run into the well and its upper end may be bolted or otherwise secured to the usual tubing head at the ground surface. The well pump, not shown, is then run in on the sucker rod or pump operating rod. In the preferred mode of employing the invention the full weight of the pump and the string of pump rods is imposed on the tubing. The combined weight of the pump and the pump rod applied to the tubing T adjacent its lower end elongates or stretches the tubing, putting the tubing under tension. It will be assumed that the pumping assembly includes the usual foot valve which prevents the discharge of fluid from the lower end of the tubing. When the pump has been seated as above described the string of tubing T is filled with fluid. The weight of the long column of fluid thus provided in the tubing T subjects the tubing to further elongation and tensioning. It is to be observed that when the string of tubing T is subjected to the combined weight of the pump, the string of pump rod and the complete fluid column that it is subjected to a greater tensioning force than at any time during subsequent pumping operations. Filling of the tubing T with liquid as just described, is accompanied by automatic operation of the slips 24.

As the column of liquid builds up in the tubing T the pistons 36 are subjected to increasing hydrostatic pressure. When the tubing is completely filled the pistons 36 are subjected to the maximum hydrostatic pressure and will have been actuated upwardly to expand the slips 24 into tight gripping engagement with the casing C.

C. It will be seen how the hydrostatic pressure acting upwardly against the pistons 36 moves the pistons, the sleeve 27 and the slips 24 upwardly. Upward movement of the slips 24 along the inclined faces 21 produces outward movement or expansion of the slips and causes the slips to tightly grip the internal surface of the casing C. Thus, the slips 24 are fully and effectively operated into tight gripping engagement with the casing C when the string of tubing T is stretched and elongated to the maximum extent.

Following the actuation of the slips 24, as just described, the pump operating rod may be pulled upwardly to "space" the pump and the usual or regular pumping operations may be carried on. The raising of the pump rod removes a substantial part of the load or weight from the tubing T and the tubing tends to contract. However, the slips 24 being held in tight gripping engagement with the interior of the casing C prevent this contraction of the tubing T and maintain the tubing under tension. During the pumping operations the movement of the fluid column in the tubing T, the friction at the pump and the pump rod movement will tend to cause moving or "working" of the tubing T. However, the slips 24 being in tight gripping engagement with the casing C and engaged between the casing and the ribs 22 dependably hold the tubing T against such movement or "working." So long as the tubing T is maintained under tension through the gripping action of the slips 24 there can be little or no movement or "working" of the tubing. Accordingly, the tubing and the casing C are not subjected to the wear which usually accompanies the working of the tubing.

When it becomes necessary or desirable to withdraw the tubing T from the well the column of liquid is drained from the tubing. This results in the automatic release of the slips 24. When the liquid is drained from the tubing T the hydrostatic pressure is removed from the pistons 36 and the pistons are free to return to their unactuated positions. The weight of the sleeve 27, links 30 and slips 24 assisted by the spring 33 automatically retracts the slips 24. The dove-tailed splines 23 and grooves 25 assure positive retraction of the slips. Because the slips 24 are freed or released automatically upon draining of the tubing T the tubing may be pulled from the well immediately following the draining operation and no manipulation of the tubing is required to release the anchor. In this connection it is to be observed that the operation of the anchor is entirely automatic, that is, it is unnecessary to manipulate or operate the tubing T in order to actuate the anchor or to release the anchor.

The invention contemplates that the anchor may be employed either in the position illustrated in the drawing or in an inverted position. With the anchor employed in the position illustrated in the drawing there is absolutely no danger of the slips 24 interfering with the free withdrawal or pulling of the tubing T subsequent to draining of the tubing. With the anchor inverted from the position illustrated in the drawing it is necessary that the tool be constructed so that the slips 24 will be positively retracted from the casing C when the tubing T is drained. Such positive retraction of the slips 24 may be effected by the spring 33 or the equivalent.

Having described only a typical preferred form and application of my invention, I do not wish

to be limited or restricted to the specific details herein set forth, but wish to reserve to myself any variations or modifications that may appear to those skilled in the art and fall within the scope of the following claims.

Having described my invention, I claim:

1. In combination, a well tubing, and an anchor for the tubing comprising a tubular body adapted to be interposed in a well tubing, slip means carried by the body for gripping the wall of the well to hold the body and tubing against upward movement, and means adapted to be actuated by the hydrostatic pressure of a column of fluid in the tubing for operating the slip means.

2. A tubing anchor for anchoring a string of well tubing in a well comprising a tubular body, connecting means for connecting the body in the string of well tubing, wedge slip means carried by the body for gripping the well casing to hold the tubing string against upward movement, and cylinder and piston means on the body actuated by the hydrostatic pressure of the column of fluid in the tubing for operating the slip means.

3. A tubing anchor for anchoring a string of well tubing in a well comprising a tubular body, connecting means for connecting the body in the string of well tubing, a part on the body having an inclined surface, a gripping slip operable into engagement with the well casing through movement along said surface, and means operable by the hydrostatic pressure in the tubing for holding the slip in the position on said surface where it grips the well casing to hold the tubing against upward movement.

4. A tubing anchor for anchoring a string of well tubing in a well comprising a tubular body, means for connecting the body in the string of well tubing so that the opening of the tubular body forms a part of the passage through the tubing string, a part on the body having an inclined surface, a gripping slip operable into engagement with the well casing through movement along said surface, and means adapted to be operated by the hydrostatic pressure in the tubing for holding the slip in the position on said surface where it grips the well casing to hold the tubing against upward movement, said means comprising a cylinder in the body having communication with the interior thereof, and a piston in the cylinder operatively associated with the slip.

5. A tubing anchor for anchoring a string of well tubing in a well comprising a tubular body, means for connecting the body in the string of well tubing, the body having a chamber in communication with the interior of the tubing and a cylinder opening in communication with the chamber, a part on the body having an inclined surface, a slip operable outwardly into gripping engagement with the casing when moved along said surface, and a piston operable in said opening by the hydrostatic pressure in the tubing for moving the slip along said surface to actuate the slip into gripping engagement with the well casing and to hold the slip actuated so that the tubing string is held against upward movement.

6. A tubing anchor for anchoring a string of well tubing in a well comprising a tubular body, means for connecting the body in the string of well tubing so that the opening through the tubular body forms a part of the passage through the tubing string, said passage containing a column of liquid extending to the top of the well, a part on the body having an inclined surface,

a gripping slip operable into engagement with the well casing through movement along said surface, cylinder and piston means on the body operable by the hydrostatic pressure in the tubing passage for moving said slip along said surface, and spring means for retracting said slip when the hydrostatic pressure is reduced.

7. A device for anchoring a string of well tubing in a well casing comprising a tubular body, means for connecting the body in the tubing string to form a part thereof, the body having inclined surfaces, slips operable along said surfaces to grip the casing, a sleeve shiftable on the body and operatively connected with the slips, the body having a plurality of cylinder openings in communication with the interior of the tubing, and pistons in said openings operable by the hydrostatic pressure in the tubing to move the sleeve and thus actuate the slips to grip the casing and hold the tubing against upward movement.

8. A device for anchoring a well tubing in a well casing comprising a tubular body adapted to be interposed in the tubing, the body having inclined surfaces, slips operable along said surfaces to grip the casing, a sleeve shiftable on the body and operatively connected with the slips, the body having one or more cylinder openings in communication with the interior of the tubing, and pistons in said openings operable by the hydrostatic pressure in the tubing to move the sleeve and thus actuate the slips to grip the casing, the weight of the slips and sleeve tending to move the slips to retracted positions when the hydrostatic pressure drops.

9. A device for anchoring a well tubing in a well casing comprising a tubular body adapted to be interposed in the tubing, the body having inclined surfaces, slips operable along said surfaces to grip the casing, a sleeve shiftable on the body and operatively connected with the slips, the body having one or more cylinder openings in communication with the interior of the tubing, pistons in said openings operable by the hydrostatic pressure in the tubing to move the sleeve and thus actuate the slips to grip the casing, and spring means for retracting the slips when said hydrostatic pressure drops.

10. A device for anchoring a well tubing in a well casing comprising a tubular body adapted to be interposed in the tubing, the body having inclined surfaces, slips operable along said surfaces to grip the casing, a sleeve shiftable on the body and operatively connected with the slips, the body having one or more axial cylinder openings in communication with the interior of the tubing, and pistons in said openings operable by the hydrostatic pressure in the tubing to push said sleeve axially of the body and thus move the slips along said surfaces.

11. A device for anchoring a well tubing in a casing comprising a tubular body to be interposed in the tubing, the body having a chamber communicating with the interior of the tubing and axial cylinder openings leading from the chamber, spaced sloping parts on the exterior of the body, slips operable along said parts to be moved into gripping engagement with the casing, a sleeve shiftable on the body, operative connections between the sleeve and slips, and pistons operable in said openings to move the sleeve and thus operate the slips along said parts.

12. A device for anchoring a well tubing in a casing comprising a tubular body to be interposed in the tubing, the body having a chamber communicating with the interior of the tubing and

axial cylinder openings leading from the chamber, spaced sloping parts on the exterior of the body, slips operable along said parts to be moved into gripping engagement with the casing, a sleeve shiftable on the body, operative connections between the sleeve and slips, a spring in said sleeve reacting between the body and sleeve to yieldingly hold the sleeve in a position where the slips are free of the casing, and pistons operable in said openings to move the sleeve and thus operate the slips along said parts.

13. A device for anchoring a well tubing in a casing comprising a tubular body to be interposed in the tubing, the body having a chamber communicating with the interior of the tubing and axial cylinder openings leading from the chamber, spaced sloping parts on the exterior of the body, slips operable along said parts to be moved into gripping engagement with the casing, a sleeve shiftable on the body, operative connections be-

20 tween the sleeve and slips, and pistons operable in said openings to move the sleeve and thus operate the slips along said parts, the pistons projecting into said chamber at all times to prevent sanding up of the cylinder openings.

14. A device for anchoring a well tubing in a casing comprising a tubular body to be interposed in the tubing, the body having a chamber communicating with the interior of the tubing and axial cylinder openings leading from the chamber, spaced downwardly and inwardly sloping parts on the exterior of the body, slips operable along said parts to be moved into gripping engagement with the casing, upwardly and outwardly facing teeth on the slips for gripping the casing, a sleeve shiftable on the body, operative connections between the sleeve and slips, and pistons operable in said openings to move the sleeve and thus operate the slips along said parts.

JOHN S. PAGE.
